DESIGN FOR AN AUTOMOBILE EXHAUST SHROUD

Louis A. Koch, Louisville, Ky.

Application September 23, 1938, Serial No. 80,064

Term of patent 14 years

To all whom it may concern:

Be it known that I, Louis A. Koch, a citizen of the United States, residing at Louisville, in the county of Jefferson and State of Kentucky, have invented a new, original, and ornamental Design for an Automobile Exhaust Shroud, of which the following is a specification, reference being had to the accompanying drawings, forming a part thereof.

In said drawings:

Figures 2, 3, and 4, respectively, are top plan, side elevation, and bottom plan views thereof.

I claim:

The ornamental design for an automobile exhaust shroud, as shown.

LOUIS A. KOCH.
